UNITED STATES PATENT OFFICE.

ADAM SCHEID AND CARL SCHEID, OF HARRISON, NEW JERSEY.

COMBINED DOOR SPRING AND CHECK.

SPECIFICATION forming part of Letters Patent No. 611,285, dated September 27, 1898.

Application filed October 30, 1897. Serial No. 656,879. (No model.)

To all whom it may concern:

Be it known that we, ADAM SCHEID and CARL SCHEID, citizens of the United States, residing at Harrison, in the county of Hudson 5 and State of New Jersey, have invented certain new and useful Improvements in a Combined Door Spring and Check; and we do hereby declare the following to be a full, clear, and exact description of the invention, such 10 as will enable others skilled in the art to which it appertains to make and use the same, reference being had to the accompanying drawings, and to letters of reference marked thereon, which form a part of this specification.

15 The present invention has reference to a novel form of combined door spring and check in which the opened door is closed partially by the action of a spring and after the door is nearly closed the tension of the spring is at 20 first opposed to the action of the air which is compressed in front of the piston to act as a check to the closing of the door and prevent the slamming or noisy closing of the same, and then the compressed air is conducted 25 back of the piston to remove the resistance from in front of a spring-actuated piston to permit the spring to securely effect the noiseless closure of the door.

30 The primary object of this invention, therefore, is to provide a combined door spring and check acting in the manner just stated, first, to partially and rapidly close the door by the action of a spring against an air-cushion in the front end of the cylinder, thus by the 35 compression of the air in front of the piston serving as a door-check, and, finally, to remove the resistance of the air from in front of the piston by allowing it to escape to the rear thereof to permit the final closing movement of the spring.

40 Other objects of this invention are to provide a novel adjusting means whereby the tension of the spring for closing the door can be increased or decreased at will, to provide a novel means for operatively attaching the 45 spring to its holding-spindle, to provide an improved means for attaching the cylinder of the device to the door, and to provide an improved means of connection and novel construction of lever and crank-arms for operatively connecting the parts of the device which

are attached to the door to the bracket secured on the door-frame.

Other objects of this invention not here specifically set forth will be fully described 55 in the accompanying specification.

Finally, the principal object of this invention is to provide a combined door-spring and door-check of the character and for the purposes hereinabove specified the several parts 60 of which shall be of a simple and durable construction and shall be effective in their operations.

With these several ends in view the invention consists in the novel door-check herein 65 set forth and in the several arrangements and combinations of parts as well as in the details of the construction thereof, all of which will be fully described in the accompanying specification and finally embodied in the 70 clauses of the claim.

The invention is clearly illustrated in the accompanying drawings, in which—

Figure 1 is a top view of the combined door spring and check embodying the principles 75 of our invention, and Fig. 2 is a front or face view of the same. Fig. 3 is a vertical section taken on line 3 3 in Fig. 2, and Fig. 4 is a horizontal section taken on line 4 4 in the same figure. Fig. 5 is a horizontal section, 80 on an enlarged scale, taken on line 5 5 in said Fig. 2, illustrating the general arrangement of the movable parts of the device in their normal and inoperative positions when the door is closed. Fig. 6 is a similar view of 85 the device, the movable parts being represented in elevation and in their respective positions when the door is partly opened; and Fig. 7 is a similar view of the parts illustrated in said Fig. 6, representing the mov- 90 able parts of the device in their fully-operated positions when the door has been entirely opened. Fig. 8 is a perspective view of a spindle connected with the device. Fig. 9 is a face view of a piston of a slightly-modified form of construction; and Figs. 10 and 11 are horizontal and vertical sections taken on lines 10 10 and 11 11, respectively, in said Fig. 9. Fig. 12 is a detail section of that part of the operating-lever attached to the operating-spindle, said section being taken on line 100 12 12 in Fig. 2. Fig. 13 is a side view of the

adjustable connecting-arm connected with the door-frame and operating-lever; and Fig. 14 is a vertical cross-section of the same, taken on line 14-14 in said Fig. 13. Fig. 15 is a detail sectional view of a portion of the air-cylinder, illustrating the same provided in the end with a screw cover or head.

Similar letters of reference are employed in all of the above-described views to indicate corresponding parts.

In said drawings, A indicates the complete door-spring and door-check, combining a spring and shaft chamber consisting of a vertical cylinder *a* and an air and piston chamber consisting of a horizontal cylinder *a'*, having a reduced portion or barrel *a²* and opening into and extending on either side of said vertical cylinder. Said reduced portion or barrel *a²* forms a suitable guide, the purpose of which will be hereinafter more fully set forth. Said barrel *a²* is closed at its free end in any suitable manner, preferably by means of a cap *b*, substantially as illustrated. The open end of said cylinder *a'* is closed by means of a cover or cap *c*, which is secured to said open end of said cylinder by means of screws *c'*, as indicated in Figs. 2 and 4, or said cap *c* can be screwed into the screw-threaded end portion of the cylinder *a'*, as clearly indicated in Fig. 15. Said cap or cover *c*, as will be seen from Figs. 5, 6, and 7, is preferably provided with an enlargement *c²*, having a recess *c³*, which extends into the forward end of the said cylinder *a'*. Directly opposite said recess *c³* is an enlargement or boss *c⁴*, having a screw-threaded hole *c⁵* in communication with said recess *c³* for the reception of a suitable screw *c⁶*, having a groove or grooves *c⁷*, whereby when said screw is screwed in or out by means of a suitable finger-piece *c⁸* and a suitable lock-nut or disk *c⁹* on said screw the hole or opening *c⁵* can be made large or small to regulate the size of the air-duct for the admission or emission of the air into or from the cylinder *a'*. Said cylinder *a'* and the barrel *a²* are provided with suitable lugs or ears *a³* and *a⁴*, having slotted openings *a⁵*, whereby the complete device can be slipped over the heads of the previously-attached screws in the door, and thereby secured in place with greater ease than when the ears or lugs *a³* and *a⁴* are provided with the usual forms of screw-receiving holes.

The vertical cylinder *a* is provided at the bottom with a perforated hub *a⁶*, to which may be detachably secured, by means of a set-screw *d'*, a cap *d*, substantially as illustrated in Fig. 3. Rotatively arranged in said tubular hub *a⁶* and in the tubular portion *d²* of the cap *d* is a spindle *e*, having an enlargement *e'*, forming a shoulder for operatively arranging said spindle on the inner surface *a'*, surrounding the hole in said hub *a⁶*. Said spindle is provided with a plain cylindrical sector *e²*, and directly opposite said sector *e²* is a second sector *e³*, having the spur-teeth *e⁴*, usually five in number, substantially as illustrated. The end

teeth of the sector *e³* are connected with the respective ends of the sector *e²* by the arc-shaped portions *e⁵* and *e⁶*, substantially of the curvatures illustrated in said Figs. 5, 6, and 7. Directly above said sectors *e²* and *e³* and on the portion *e⁷* of the spindle *e* the latter is provided with one or more holding lugs or ribs *e⁸*, in engagement with any one of which can be placed the bent or hook-shaped end *g'* of a stiff spiral spring *g*. Said spring encircles the said portion *e⁷* of the spindle *e* and has its outer end *g²* made in the manner of a hook, whereby said hook end *g²* of the spring can be operatively arranged in a slotted part *f'* of an annular projection forming a shoulder *f²* on a cap or cover *f*, as clearly illustrated in Fig. 4. Said shoulder *f²* of the cap *f* fits into the opening in the top of the vertical cylinder *a*, the annular rim of said cap *f* resting upon the annular edge of said cylinder and being secured in place by means of a set-screw *j*, the inner end of which can be brought into holding engagement with one of a number of depressions *f³* in said shoulder *f²*, as will be clearly seen from an inspection of said Fig. 2. Upon the outer face of said cap *f* is a nut portion *f⁴* and a hub *f⁵*, both of which, with the main portion of said cap *f*, are provided with a hole or opening, in which is arranged the upper portion of the spindle *e*, as clearly illustrated in Figs. 2 and 3. To properly regulate the tension of the spring *g*, an ordinary wrench is placed over the nut portion *f⁴* of the cover *f* and the set-screw *j* sufficiently loosened. By operating the wrench the cover *f* can be turned and the spring *g* tightened upon the spindle *e*, as will be understood, and when sufficiently adjusted then the inner end of the set-screw *j* is again screwed into one of said depressions *f³* in the shoulder *f²* of said cover *f*, whereby the parts will thus be held in their adjusted positions. Capable of sliding longitudinally in said horizontal air-cylinder *a'* is a piston *h*, having a rearwardly and upwardly extending rod *h'*, which is bent or formed in a peculiar manner and has the curved surfaces *h²* and *h³*. Said rod *h'* is provided at its rearwardly and upwardly extending part with a rack portion *h⁴*, having the teeth *h⁵*, and a cylindrical end portion *h⁶*, as clearly illustrated in the several figures of the drawings. Said teeth *h⁵* are normally in operative mesh with the teeth of the sector *e³* on the spindle *e*, and when the latter is operated the said toothed sector will force the cylindrical end portion *h⁶* of the rack into the barrel or cylinder *a²*, hereinabove mentioned, said barrel or cylinder acting as a guide to prevent the jamming and consequent inoperativeness of the moving parts of the device. As will be seen from Fig. 5, the diameter of said piston *h* is smaller than the inner diameter of the cylinder *a'*, and secured against the face of said piston by means of a nut *h⁷* and a disk or plate *h⁸* on the screw portion *h⁹* is a cup-shaped flexible disk *k*, the annular and bent edge of which is in frictional sliding engagement

with the inner surface of the cylinder a' , as clearly illustrated. To permit the compressed air in said cylinder a' between the front of said piston h and the back of the cap or cover c to pass back of the piston when the door is nearly closed and to remove the resistance of the air from in front of said piston, said cylinder is provided in a suitable part of its surrounding wall with a duct a^8 and the openings a^9 and a^{10} for establishing a communication between said duct and the inner part of the cylinder a' . The opening a^9 is formed by drilling from the outside of the cylinder a' into the duct a^8 and through into the inner portion of said cylinder, after which that portion of the hole a^9 between the duct and the outer surface of the cylinder is closed by a suitable plug a^{11} .

In lieu of a solid piston h and solid disk k we may dispense with the larger disk or plate h^8 , hereinabove mentioned, and a small washer h^{10} on the screw portion h^9 may be employed and the piston provided with holes or perforations h^{11} and the flexible disk with holes or perforations k' . The positions of the holes in the piston and said disk k alternate, as clearly indicated in Figs. 9, 10, and 11, whereby while the door is being opened the air in said cylinder a' at the back of the piston will pass through the holes h^{11} and between the slightly-distorted flexible disk k and through the holes k' therein; but on the return stroke while the door is being closed then said flexible disk k will be firmly forced against the face of the piston h , with its annular edge in close contact with the inner surface of the cylinder a' . Thus the holes h^{11} in the piston will become closed and no air can pass from in front of the piston to the back thereof, whereby a perfect air-check is the result.

To operate the spindle e and the parts connected therewith when attached to a door, the upper end of said spindle has a recess e^9 , in which is arranged a suitable projection i' , formed in the split eye i^2 of an actuating-lever i . Said split eye has a pair of lugs i^3 and a screw i^4 , whereby said lever i can be securely and operatively connected with the said spindle e . Pivotaly attached to the forward end of said lever i on a stud or pivot i^5 is a connecting-rod l , which is adjustably connected with a second connecting-rod l' , said rod being pivoted, by means of a pin m' , to a bracket m , secured to the door-frame, as will be understood from an inspection of Figs. 1 and 2. As will be more especially seen from Figs. 13 and 14, said arm l slides between a pair of guides l^2 on the arm l' , said arm l' also having a longitudinally-arranged opening l^3 , bounded by the corrugated sides l^4 and l^5 . Said arm l is provided with a screw-threaded socket l^6 , into which is screwed a bolt l^7 , which extends through said opening l^3 in the arm l' and has a head above said arm for locking a plate l^8 , provided with the corrugations l^9 , directly to the corrugated parts

of the said rod or arm l' , whereby the two arms l and l' can be securely locked or connected in their properly-adjusted positions. 70

The operation of the several parts of the hereinabove-described combined door spring and check is as follows: The combined cylinders a , a' , and a^2 are securely fastened to the door and the bracket m to the door-frame, with the actuating-lever i properly attached to the spindle e and the connecting-rods l and l' in their operative and properly-adjusted positions. As soon as the door is being opened the spindle e is rotated in its proper bearing portions in the vertical cylinder a , whereby the spring g is tightly wound upon said spindle e , and the spur-teeth on the sector e^3 will cause the piston h and its several parts to move from their normally inoperative positions indicated in Fig. 5 to the positions represented in Fig. 6, and the edge between the sector portion e^2 and the arc e^5 will come in contact with a portion of the curved part h^2 , as clearly indicated in said Fig. 6. This action of these parts will still cause the piston h and its parts to move for a short distance in a forward direction until the piston and its parts have assumed the positions indicated in Fig. 7, in which positions these parts will 90 remain inactive. By this time the door has been but partly opened, and while being continued to be opened the spindle e , its spring g , and the sectors e^2 and e^3 will finally take the positions represented in said Fig. 7. The 100 movements of the lever and connecting-rods l and l' will be understood. When the person has entered and the door is released, the tension of the spring g causes the door to close very rapidly until the sector-teeth engage with the curved part h^2 and the teeth on the rack portion of the rod connected with the piston h are again brought into operative mesh. The piston is thus rapidly returned to the forward end portion of the cylinder a' , 110 whereby the air in front of the piston is greatly compressed and the closing movement of the several parts of the device and that of the door is suddenly checked, while some of the air escapes through the grooved screw or 115 bolt in the head c of said cylinder. As soon as the piston has again reached the position near the inner surface of said head c the remaining air will rush through the duct a^8 and out of the opening a^9 , now back of the piston, 120 to the other side of the surrounding edge of the flexible disk k , connected with said piston h , thereby removing all resistance to the final closing action of the spring g , whereby the door will receive a slightly-faster closing 125 motion and will finally be closed without any undue noise or slamming.

From an inspection of the several figures of the drawings it will be seen that the cap d can be detached from the hub a^6 and placed on 130 the hub f^5 of the cap f , the lever i having been previously disconnected from said hub f^5 , whereby by simply reversing the entire casing without disturbing the working parts

therein said lever can now be attached to the end of the spindle e projecting from said hub a^6 . Thus it will be evident that the same device can be used in connection with any door no matter whether it opens to the right or to the left.

The outer surfaces of the several cylinders of the device may be suitably ornamented.

By means of our novel construction of combined door spring and check we have devised a simple and operative device for effectively closing a door without slamming and one which enables the door to be opened easily without the necessity of drawing the piston 15 against a body of air, the spring on the spindle e being the power for automatically closing the door and the compressed air in front of the piston on the return of the several parts to their initial positions acting simply 20 to overcome the rapidly-closing movement of the door.

Of course it will be evident that many changes may be made in the several arrangements and combinations of the parts and the 25 details of the construction thereof without departing from the scope of our invention, and hence we do not limit ourselves to the exact arrangements and combinations of the parts nor to the details of the construction 30 thereof as described in the accompanying specification and as illustrated in the drawings forming a part thereof.

Having thus described our invention, what we claim is—

35 1. A combined door spring and check, comprising a vertical cylinder forming a spring and shaft chamber and a horizontal air and piston chamber consisting of a horizontal cylinder having a reduced cylindrical portion 40 and extending on either side of said vertical cylinder, the central longitudinal axes of the main part of said horizontal cylinder and the said reduced part being in different but parallel planes both to one side of the central 45 vertical axis of said vertical cylinder, a rotatively-arranged spindle in said vertical cylinder, a spiral spring on said spindle, mechanism connected with said spindle for actuating the same and its spring, a toothed sector 50 on said spindle, a piston and piston-rod in the main portion of said horizontal cylinder, a rearwardly and upwardly extending rod connected with said piston, and a toothed rack at the free end of the bent part of said 55 rod fitting and sliding in the reduced portion of said horizontal cylinder, the teeth of said rack being in intermittent mesh with the teeth of said sector, substantially as and for the purposes set forth.

2. A combined door spring and check, comprising a vertical cylinder forming a spring and shaft chamber and a horizontal air and piston chamber consisting of a horizontal cylinder having a reduced cylindrical portion and extending on either side of said vertical cylinder, the central longitudinal axes of the main part of said horizontal cylinder and the said reduced part being in different but parallel planes both to one side of the central vertical axis of said vertical cylinder, a rotatively-arranged spindle in said vertical cylinder, a spiral spring on said spindle, mechanism connected with said spindle for actuating the same and its spring, a toothed sector on said spindle, a piston and piston-rod in the main portion of said horizontal cylinder, a rearwardly and upwardly extending rod connected with said piston, and a toothed rack at the free end of the bent part of said rod fitting and sliding in the reduced portion of said horizontal cylinder, said piston-rod having curved portions h^2 and h^3 , and said sector having curved parts e^5 and e^6 , all arranged to intermittently cause the active engagement and disengagement of said toothed rack with said toothed sector, substantially as and for the purposes set forth.

3. A combined door spring and check, comprising a cylinder having bearing portions, and a rotatively-arranged spindle thereon, a spiral spring on said spindle, mechanism connected with said spindle for actuating the same and its spring, a toothed sector on said spindle, an air-cylinder connected with said spindle-carrying cylinder, a piston and piston-rod in said cylinder, a toothed rack connected with said piston, said piston-rod having curved portions h^2 and h^3 on said piston-rod, a sector portion e^2 on said spindle having curved parts e^5 and e^6 , all arranged to intermittently cause the active engagement and the disengagement of said toothed rack with said toothed sector, substantially as and for the purposes set forth.

4. In combination, with an air-cylinder, a piston h having perforations h^{11} , and a flexible disk k thereon having holes k' , said holes being alternately spaced with respect to said piston and the disk k , substantially as and for the purposes set forth.

In testimony that we claim the invention set forth above we have hereunto set our hands this 27th day of October, 1897.
